W. H. FLIEHMANN

CLEANING DEVICE

Filed Sept. 30, 1925

UNITED STATES PATENT OFFICE.

WILLIAM H. FLEHMANN, OF ST. CHARLES, MISSOURI.

CLEANING DEVICE.

Application filed September 30, 1925. Serial No. 59,633.

This invention relates to improvements in cleaning devices primarily adapted for cleaning carpets and the like and which includes a plurality of cups carried by a handle member which when struck against a rug will expel the dust within the rug from the opposite sides thereof.

Another object of the invention comprehends a plurality of open rings which are adapted to receive both rubber and metallic bells and when contacting one side of a carpet, or quilt by beating will create a vacuum by the blow from the opposite of the beaten side, simultaneously from both sides of the article cleaned by repeated strikes or blows.

With the above and other objects in view, the invention further includes the following novel features and details of construction, to be hereinafter more fully described, illustrated in the accompanying drawing and pointed out in the appended claims.

In the drawing:

Figure 1 is an elevation of my invention.

Figure 2 is a side elevation with parts broken away.

Figure 3 is a fragmentary portion in elevation of a modified form of my invention.

Figure 4 is a fragmentary side elevation of the modification.

Figure 5 is a top plan view of a modified form of the invention.

Referring to the drawing in detail, wherein like characters of reference denote corresponding parts, the reference character 10 indicates a single length of wire which is bent intermediately upon itself and having its ends arranged within corresponding channels, not shown, within a split handle 11 in order that the said wire will be held firmly within the handle. As clearly illustrated in Figures 1 and 2 of the drawing the portions of the wire 10 after being bent intermediately upon themselves extend in spaced parallel or staggered relation and which include alternate arrangement of the open looped portions 12. The loops 12 are adapted to receive rubber bells 13 having annular groove 14 upon their upper portions in order that the said bells 13 will be held firmly in place within the loops 12. By the same token I provide a plurality

of relatively large rubber bells 15 having annular grooves 16 provided adjacent their open ends and which are adapted to receive therein the relatively large looped portions 17. It is thus noted from the assembly of my device as aforementioned in the preferred and modified forms, alternate arrangement of bells may be provided secured in different manners to provide resilient bells in alternate arrangement so that the maximum efficiency of my invention will be facilitated.

Figure 5 illustrates a device providing a length of wire 10³ bent intermediately upon itself with its ends received within a handle 11³, the outer and intermediate portion of the wire 10³ forms a segment 12³ provided with a plurality of loops 13² within which may be mounted any of the bells shown in any of the prior figures and which owing to the structure and arrangement of parts thereof will beat in an arc instead of a longitudinal plane with respect to its handle.

In the mode of operation of the present invention it is clearly apparent that an operator upon grasping either the handles 11 or 11³ provided in the preferred and modified forms of my invention and upon bringing the peripheries of the bells into engagement with one side of a rug in the process of beating, it is manifest that the dust and the like within the rug will be forced outwardly to the opposite side of the rug and upon such strikes or blows a rebounding action similar to the bouncing of a rubber ball, will take place which makes the beater easy to manipulate.

The invention is susceptible of various changes in its form, proportions and minor details of construction, and the right is herein reserved to make such changes as properly fall within the scope of the appended claims.

Having thus described my invention, what is claimed is:

1. A device of the character described comprising a single length of wire bent intermediately its ends and having its free end portions extending in spaced parallel relation, the side portions being formed with a plurality of alternately arranged open

loops, and correspondingly shaped suction members received within said loops.

2. A device of the character described including a single length of wire bent upon itself and having its free end portions extended in spaced parallel relation, the side portions each having a plurality of spaced open loops with the loops on one side por-

tion arranged alternately relative to the loops on the other side portion, and bell shaped suction members having annular grooves positioned within said loops, as and for the purpose specified.

In testimony whereof I affix my signature.

WILLIAM H. FLIEHMANN.
